OUT-SWINGING WINDOW CONSTRUCTION

Hubert O. Carroll, Painesville, Ohio

Application February 2, 1939, Serial No. 254,257

15 Claims. (Cl. 268—117)

In the usual arrangement of an out-swinging or casement type of window, it has always been a matter of particular difficulty to employ window screens, and insofar as these have been possible they have, in the simple hand-operated type of window required the placement of the screen on the inside and the removal of the screen every time the window was to be opened and closed, or in special instances where window-operating means have been provided, in order to make possible the manipulation of the window without disturbing the screen, it has involved the placement of operating mechanism on the sill or lower portion of the frame such as to be very much in the way. In accordance with the present invention, a window of casement type may be opened and shut easily, by operating connections permitting a window screen or storm window to remain in position on the inside without disturbance, and the window sill portion is wholly free from obstruction, thereby maintaining usefulness and sightliness of the window sill.

To the accomplishment of the foregoing and related ends, the invention, then, comprises the features hereinafter fully described, and particularly pointed out in the claims, the following description and the annexed drawing setting forth in detail certain illustrative embodiments of the invention, these being indicative however, of but a few of the various ways in which the principle of the invention may be employed.

In said annexed drawing:

Fig. 1 is a perspective view of an embodiment of the invention, taken from the inside; Fig. 2 is a transverse section taken on the plane indicated by line II—II, Fig. 1; Fig. 3 is a slightly enlarged perspective view showing the sash and detail of the operating mechanism; Fig. 3a is a modified form; Fig. 4 is an enlarged sectional detail taken on a plane substantially indicated by line IV—IV, Fig. 3; Fig. 5 is a sectional detail at right angles to Fig. 4, being taken on a plane substantially indicated by line V—V, Fig. 4; Fig. 6 is a sectional detail taken on a plane substantially indicated by line VI—VI, Fig. 3a; and Fig. 7 is a further sectional detail taken at right angles and on a plane substantially indicated by line VII—VII, Fig. 6.

Within a framed opening 2, having sill 3, a casement type panel or sash 4 is mounted by hinges 5 to one side of the frame. Preferably, the hinges, as shown at Fig. 2 are of an offsetting form, embodying a hinge member 6 secured to the sash and connected at 7 to the outer covering hinge member 5 which in turn is

pivoted at 8 to a frame-engaging plate 9. Ordinarily one hinge at the top and one at the bottom of the sash is sufficient. Desirably, and particularly with larger windows, an abutment plate 10 may be provided on the sill 3 for the heel of the sash to ride against in opening and shutting, and such plate may be slightly concave on its edge 11, and a wear-shoe 12 may be provided on the sash, such arrangement saving strain on the hinges, particularly in operation in windy weather. The plate 10 being set down flush into the sill, is wholly unobtrusive. Secured to the upper portion of the sash is an operating arm 14, Fig. 3, to which is pivoted a link 15, which in turn is pivoted to a connection member 16 projecting from a runner 17, the latter being slideable back and forth in a guide 18, as pulled one way or another by the pull chains or equivalent cords 19, 20. The guide 18 which may be of suitably heavy sheet metal, may be secured to the upper portion of the frame by screws through the screw holes 22, and the chains or cords 19, 20, run over pulleys 23. While these latter may be mounted in the ends of the guide 18, it is generally preferable to have them in separate mounting pieces 24, which mate to the ends of the guide 18 and allow some latitude of adjustment in frame-variations. The connection member 16 is preferably provided with an adjustable take-up, as by a tightening screw or bolt 25 through a slot in the member 16, whereby the length of the connection 16 can be adjusted as required in any condition and be set tight. From the structure so far described, it will be seen that the pull chains 19 and 20 control the movement of the runner 17 and the movement of the sash 4, a pull on one chain serving to draw the runner in one direction and through the lever and hinge means 16—15—14 swing the window open, and pull on the other chain serving conversely to swing the window shut. As an additional refinement I provide a position-locking means to hold the runner and correspondingly the sash 4 in desired position, whether open or shut or at some intermediate position. This in general involves a means on the runner to engage the guide and hold, and such means may be automatically released by the pull chain itself, thereby simplifying the operation and requiring no particular attention. In the runner as shown in Fig. 3 and in further detail in Figs. 4 and 5, this locking means takes the form of expanding wedges 27, 28, Fig. 5, these riding against each other by inclined surfaces at 29, and being tensioned toward each other by a spring pull-up 30. The wedge 27 be-

ing fastened to the runner 17, and the runner being of sheet metal and riding within the guide 18 and being of channel-shape, it is seen that the spring 30 tends to wedge the members 27, 28, forcibly against the bounding-flanges of the runner 17 and thereby expand it into frictional gripping engagement in the guide 18. When however the pull chain to open the window is drawn upon, it pulls the wedging pair apart and releases the locking action of the runner against the guide. Instead of the wedging action, in some cases I may employ a dog latch, as in Figs. 3a, 6 and 7, wherein the latch or dog-lever is pivoted at 33 to the runner 17a, the latch end 34 being projectible through an opening in the runner and into stop-openings 35 in the guide 18a. With the latch provided with a slope at one side, it can easily ride along from latch-opening to latch-opening as the runner is pulled in a direction to the left as viewed in Fig. 7, and the spring 36 will hold the latch in engagement. The one pull chain is attached to the runner at a convenient point, and the other is attached to the lever end 38 of the latch. Thus, when the chain at the right in Fig. 7 is pulled, the lever 38 is drawn up into line and the latch 34 is released and continued pull on the chain draws the runner along and correspondingly pulls the window.

The operation of opening and closing the window will be entirely clear from the foregoing, it being seen that in order to close the window, it is merely necessary to pull down on chain handle 19h, this releasing the position-lock and pulling the runner and levering the sash into partly or completely closed position, as desired; and conversely by pulling down on handle 20h, the sash is opened. The sill 3 is unobstructed. Particularly conveniently also, a window screen or an inner storm window S can be placed in position against the inner stops 39 and remain there undisturbed while permitting any desired manipulation of the window beyond. With particular advantage, the guide 18 conjointly includes a screen or storm sash engaging means, as a downwardly-directed flange 40, Figs. 1, 4 and 6, to engage in a groove in the screen or storm sash, Fig. 4.

Other modes of applying the principle of the invention may be employed, change being made as regards the details described, provided the features stated in any of the following claims, or the equivalent of such, be employed.

I therefore particularly point out and distinctly claim as my invention:

1. In building construction, a framed wall-opening; an outwardly swingable sash hinge-supported at one side therein; and means for swinging said sash without presenting obstruction on the sill, including an inwardly-directed arm on the sash, a link pivoted to said arm, a runner having an adjustable-length connection to said link, a guide on the upper portion of the frame for said runner and enclosing the runner by a downwardly-directed flange, a pulley at each end of said guide, support means for each pulley, a pull chain over each pulley and having connection to said runner, said runner including a position-locking means comprising means to engage the guide, spring means forcing the same into engagement, and a connection by one of said pull chains to release the engaging means.

2. In building construction, a framed wall-opening; an outwardly swingable sash hinge-supported at one side therein; and means for swinging said sash without presenting obstruction on

the sill, including an inwardly-directed arm on the sash, a link pivoted to said arm, a runner having an adjustable-length connection to said link, a guide on the upper portion of the frame for said runner and enclosing the runner by a downwardly-directed flange, a pulley at each end of said guide, support means for each pulley, a pull chain over each pulley and having connection to said runner, said runner including a position-locking means releasing on pull of a chain.

3. In building construction, a framed wall-opening; an outwardly swingable sash hinge-supported at one side therein; and means for swinging said sash without presenting obstruction on the sill, including an inwardly-directed arm on the sash, a link pivoted to said arm, a runner having an adjustable-length connection to said link, a guide on the upper portion of the frame for said runner, and enclosing the runner by a downwardly-directed flange, a pulley at each end of said guide, support means for each pulley, a pull chain over each pulley and having connection to said runner, said runner including a position-locking means comprising an expanding wedge riding against an inclined surface, one pull chain being connected to said wedge, and spring means urging the wedge against the inclined surface.

4. In building construction, a framed wall-opening; an outwardly swingable sash hinge-supported at one side therein; and means for swinging said sash without presenting obstruction on the sill, including an inwardly-directed arm on the sash, a link pivoted to said arm, a runner having an adjustable-length connection to said link, a guide on the upper portion of the frame for said runner and enclosing the runner by a downwardly-directed flange, a pulley at each end of said guide, support means for each pulley, a pull chain over each pulley and having connection to said runner, said runner including a position-locking means comprising a dog-lever pivoted on the runner and having one end as a lever and the other end as a latch, one said pull chain being connected to said lever end, a series of stop-holes in said guide, and spring means urging the latch into locking position.

5. In building construction, a framed wall-opening; an outwardly swingable sash hinge-supported at one side therein; and means for swinging said sash without presenting obstruction on the sill, including an inwardly-directed arm on the sash, a link pivoted to said arm, a runner having an adjustable-length connection to said link, a guide on the upper portion of the frame for said runner, a pulley at each end of said guide, a pull chain over each pulley and having connection to said runner, said runner including a position-locking means comprising an expanding wedge riding against an inclined surface, one pull chain being connected to said wedge, and spring means urging the wedge against the inclined surface.

6. In building construction, a framed wall-opening; an outwardly swingable sash hinge-supported at one side therein; and means for swinging said sash without presenting obstruction on the sill, including an inwardly-directed arm on the sash, a link pivoted to said arm, a runner having an adjustable-length connection to said link, a guide on the upper portion of the frame for said runner, a pulley at each end of said guide, a pull chain over each pulley and having connection to said runner, said runner including

a position-locking means comprising a dog-lever pivoted on the runner, one said pull chain being connected to one end of said lever and the other end forming a dog-latch, a series of stop-holes in said guide, and spring means urging the latch into locking position.

7. In building construction, a framed wall-opening; an outwardly swingable sash hinge-supported at one side therein; and means for swinging said sash without presenting obstruction on the sill, including an inwardly-directed arm on the sash, a link pivoted to said arm, a runner connected to said link, a guide on the upper portion of the frame for said runner, a pulley at each end of said guide, a pull chain over each pulley and having connection to said runner, said runner including a position-locking means comprising an expanding wedge riding against an inclined surface, one pull chain being connected to said wedge, and spring means urging the wedge against the inclined surface.

8. In building construction, a framed wall-opening; an outwardly swingable sash hinge-supported at one side therein; and means for swinging said sash without presenting obstruction on the sill, including an inwardly-directed arm on the sash, a link pivoted to said arm, a runner connected to said link, a guide on the upper portion of the frame for said runner, a pulley at each end of said guide, a pull chain over each pulley and having connection to said runner, said runner including a position-locking means comprising a dog-lever pivoted on the runner, one said pull chain being connected to one end of said lever and the other end forming a dog-latch, a series of stop-holes in said guide, and spring means urging the latch into locking position.

9. In building construction, a framed wall-opening; an outwardly swingable sash hinge-supported at one side therein; and means for swinging said sash without presenting obstruction on the sill, including an inwardly-directed arm on the sash, a link pivoted to said arm, a runner connected to said link, a guide on the upper portion of the frame for said runner, a pulley at each end of said guide, a pull chain over each pulley and having connection to said runner, said runner including a position-locking means comprising means to engage the guide, spring means forcing the same into engagement, and a connection by one of said pull chains to release the engaging means.

10. In building construction, a framed wall-opening; an outwardly swingable sash hinge-supported at one side therein; and means for swinging said sash without presenting obstruction on the sill, including an inwardly-directed arm on the sash, a link pivoted to said arm, a runner connected to said link, a guide on the upper

portion of the frame for said runner, a pulley at each end of said guide, and a pull chain over each pulley and having connection to said runner, said runner including a position-locking means releasing on pull of a chain.

11. In building construction, a framed wall-opening; an outwardly swingable sash hinge-supported at one side therein; and means for swinging said sash without presenting obstruction on the sill, including an inwardly-directed arm on the sash, a link pivoted to said arm, a sash-operating runner having connection to said link, an enclosed longitudinal housing on the upper portion of the frame covering and guiding said runner, a pulley at each end thereof, and a pull chain over each pulley and having connection to said runner.

12. In building construction, a framed wall-opening; an outwardly swingable sash hinge-supported therein; and means for swinging said sash, including a link connection and a runner, a guide on the frame for said runner, and enclosing the runner by a flange directed in the general plane of the window, a pulley at each end of said guide, and a pull chain extending over each pulley and having connection to said runner, said runner including a position-locking means releasing on pull of a chain.

13. In building construction, a framed wall-opening; an outwardly swingable sash hinge-supported therein; and means for swinging said sash, including a link connection and a runner, a longitudinal enclosure on the frame for said runner, a pulley at each end thereof, and a pull chain extending over each pulley and having connection to said runner, and a position-locking means releasing on pull of a chain.

14. In building construction, a framed wall-opening; a swingable sash hinge-supported therein; and means for swinging said sash, including a link and a runner, a longitudinal enclosure on the frame for said runner, a pulley at each end thereof, a pull chain over each pulley and being connected to said runner, said runner including a position-locking means comprising means to engage said enclosure from within, spring means forcing the same into engagement, and a connection to one of said pull chains to release the engaging means.

15. In building construction, a framed wall-opening; a swingable sash hinge-supported therein; and means for swinging said sash, including a runner having a connection to the sash, a longitudinal housing enclosing said runner, means for sliding the runner including a pull connection extending into said housing, and a position-lock for said runner expanding to hold to said housing and releasing by said pull connection.

HUBERT O. CARROLL.
